US00D582122S

(12) **United States Design Patent**
Splain et al.

(10) **Patent No.:** US D582,122 S
(45) **Date of Patent:** ** Dec. 2, 2008

(54) **SHOPPING CART**

(75) Inventors: **William D. Splain**, Brooklyn Park, MN (US); **Robert D. Peota**, Minneapolis, MN (US); **Alexandre Hennen**, Cambridge, MA (US); **Allan Cameron**, Natick, MA (US); **Mark T. Ryan**, Haskell, OK (US); **David L. Pruitt, Jr.**, Brookland, AR (US)

(73) Assignee: **Target Brands, Inc.**, Minneapolis, MN (US)

(**) Term: **14 Years**

(21) Appl. No.: **29/296,975**

(22) Filed: **Oct. 31, 2007**

Related U.S. Application Data

(63) Continuation of application No. 29/280,573, filed on May 31, 2007, which is a continuation of application No. 29/271,229, filed on Jan. 12, 2007, now Pat. No. Des. 546,021, which is a continuation of application No. 29/267,189, filed on Oct. 6, 2006, now Pat. No. Des. 540,998, which is a continuation of application No. 29/238,739, filed on Sep. 19, 2005, now Pat. No. Des. 530,478.

(57) **CLAIM**

The ornamental design for a shopping cart, as shown and described.

DESCRIPTION

Shopping cart embodiments illustrated herein are useful for shopping, purchasing, holding, transporting, storing, displaying articles, and displaying information, and the like via a shopping cart.

FIG. 1 is an isometric view of a shopping cart.

FIG. 2 is a front view of a shopping cart, with a dashed box identifying a portion of the shopping cart illustrated in FIG. 3.

FIG. 3 is an enlarged front view of the portion of the shopping cart shown in the dashed box of FIG. 2.

FIG. 4 is a rear view of a shopping cart.

FIG. 5 is a right side view of a shopping cart.

FIG. 6 is a top view of a shopping cart.

FIG. 7 is a bottom view of a shopping cart; and,

FIG. 8 is a left side view of a shopping cart.

The bold broken lines immediately adjacent the shaded areas in FIGS. 1-3, 6 and 8 represent the bounds of the claimed design while all other broken lines in FIGS. 1-8 are for illustrative purposes only and form no part of the claimed design.

1 Claim, 8 Drawing Sheets
